NICHOLAS STOCK, OF KINGSTON, NEW YORK.

CHAIR-TIP.

1,356,798.

Specification of Letters Patent. Patented Oct. 26, 1920.

Application filed February 28, 1918. Serial No. 219,549.

To all whom it may concern:

Be it known that I, NICHOLAS STOCK, a citizen of the United States, and residing in Kingston; in Ulster county and State of New York, have invented certain new and useful Improvements in Chair-Tips, of which the following is a specification.

The present invention relates to improvements in chair tips, and has for its object to provide a tip for chairs or other such articles of furniture, which will be of simple and inexpensive construction, will be convenient to attach, and will prove efficient in use.

I propose in the present embodiment of my invention to provide a tip, the shank of which is immovable with respect to the pad, and which may be directly inserted in a bore previously drilled in the chair leg, and non-rotatably held therein, to the end that a special socket such as disclosed in my Patent No. 771,679 of October 4th, 1904, will be eliminated and loosening or dropping of the tip by rotation of the pad such as may be caused by constant movement about of the chairs, will be prevented. I also propose to obviate any danger of damaging or splitting the chair legs, some of which are very delicate, such damage having been caused in the past where a relatively large bore was required to be made in the leg or where a tapering screw shank was employed, and inserted without previously providing a bore in the leg.

Another object is to provide a tip which will always maintain a non-scratching surface, even though the pad portion becomes entirely worn away.

A still further object is to provide for the elastic retention of the tip in the chair leg without danger of its dropping out, at the same time permitting of its convenient removal and renewal without injury to the chair leg, and without the necessity of re-boring the same.

With these and other objects in view, embodiments of my invention are shown in the accompanying drawings, and these embodiments will be hereinafter more fully described with reference thereto, and the in-

vention will be finally pointed out in the claims.

In the drawings:

Figure 1 is a side elevation of one embodiment of my improved tip;

55

Fig. 2 is a plan view thereof;

Fig. 3 is a vertical sectional view of the end of a chair leg, showing the same bored previous to the insertion of the tip;

60

Fig. 4 is an end view thereof;

Fig. 5 is a vertical sectional view partly in elevation, showing the end of a chair leg with the tip attached;

65

Fig. 6 is a transverse sectional view taken along the line 6—6 of Fig. 5; and

65

Fig. 7 is a side elevation of a modified form of tip.

Similar reference characters indicate corresponding parts throughout the drawings.

Referring to the drawings, and more particularly to Figs. 1 and 2 thereof, the embodiment of my invention shown therein comprises a shank 10, provided with longitudinal reeds or ribs 11, and having at its upper end a tapered guide nose 12 forming 70 at the upper extremity of the reeded portion a lateral shoulder 13. The lower end of the shank is preferably plain or smooth as at 14 at that portion thereof which is embedded in the pad 15, formed of rubber or other suitable substance, and at its end is provided with a metallic head 16 of bowl shape, the said head being of gradually decreasing thickness toward its peripheral portion, and having a smooth convex exterior surface 17. The head 16 is solid at its center portion, and provided with spaced openings 18 extending therethrough inwardly of its perimeter.

The rubber tip is molded upon the head 90 16 and the rubber entering within the openings 18 prevents any possibility of rotation thereof, this result being enhanced by the relatively large wall surface 19 of the said openings. The bowed head provides a secondary non-scratching wearing surface when the pad 10 becomes worn to such an extent that the head is exposed, so that even though the rubber becomes worn out, there will be no danger of marring the floor. The 100

rubber between the upper surface of the pad and the interior surface of the head 16 is substantially dove-tailed in cross section, so that lateral displacement of the pad away from the shank is prevented, which lateral displacement would readily take place under the heavy strains exerted upon the pad should the head be flat or disk shaped.

Previous to attaching the tip to the chair

10 leg, the chair leg 20 is provided with a cylindrical bore 21 preferably by means of a drill bit, the said bore being of a diameter slightly less than that of the shank 10, or in other words, equal to the diameter of 15 the shank less the reeded portion.

The beveled nose 12 is inserted in the bore, and the shoulder 13 enables the shank to be properly positioned prior to driving the same into the bore. At the same time 20 the upper ends of the reeds formed by the shoulders, constitute sharp cutting edges which cut into the wood of the chair leg. The shank is driven straight into the bore, and the wood enters between the reeds as 25 at 22, as clearly indicated in Figs. 5 and 6, so that rotation of the shank is prevented, and in turn the connection between the shank and the pad prevents rotation of the pad with respect to the chair leg.

30 Because of the elasticity of the wood, the shank is tightly held within the bore, and there is no danger of the same dropping out. In order to remove the tip after the same has become worn, it is only necessary to pull the shank, without turning, from the bore, or a suitable tool may be inserted between the end of the chair and the tip and the shank. A new tip may 35 thereupon be inserted, the reeds of the same being engaged with the channels formed in the bore by the removed tip, and as above 40 stated, the elasticity of the wood will serve to positively retain the same without danger of dropping out.

45 In Fig. 7, I have illustrated a slightly modified form of tip, in which the reeded shank 10 is non-rotatably secured to a metal cap 23 to which there is secured by means of an over-turned flange 24 a pad 25 50 formed of leather or other suitable substance. The coöperation between this tip

and the chair leg is the same as that of the tip shown in Figs. 1 and 2, that is, the pad is non-rotatable with respect to the shank, and the shank is non-rotatable with respect 55 to the chair leg.

I have illustrated preferred and satisfactory embodiments of my invention, but it is obvious that changes may be made therein within the spirit and scope thereof, 60 as defined in the appended claim.

I claim:—

An improved furniture pad comprising an attachment member having a shank, a convex concave circular head at one end of 65 the shank integral therewith and coaxial thereto and flaring from the shank and at its interior side concave to the shank to form a bowled circular head, and a single piece cushion member molded on said end 70 of the shank centrally and coaxially with the shank and bowled circular head, completely inclosing and covering all parts of said circular head, said shank having on its upper end an upwardly tapering guide 75 nose and provided with longitudinal ribs extending from said guide nose to a point adjacent to said bowled circular head, the shank also having a smooth reduced portion 80 within the concavity of said bowled head 80 and extending from the inner surface of the latter to the lower ends of said ribs, said circular head having substantially circular openings therethrough arranged about the shank and spaced forwardly from the rim 85 of the head, said rim being continuous and uninterrupted and said openings having annular flat walls whereby to prevent cutting of said cushion and to support said cushion from vertical and lateral displacement from 90 the head, the exterior side of said bowled circular head and the tip end of the shank being on the same continuous unbroken convex curve.

In testimony that I claim the foregoing 95 as my invention, I have signed my name in presence of two subscribing witnesses.

NICHOLAS STOCK.
